INVENTOR:

Charles A. Williams

By his Attorney, Francis E. Roche

UNITED STATES PATENT OFFICE.

CHARLES A. WILLIAMS, OF BROOKLYN, NEW YORK.

MULTIPLE-FUSE CARRIER.

1,237,005.

Specification of Letters Patent. Patented Aug. 14, 1917.

Application filed December 30, 1916. Serial No. 138,878.

To all whom it may concern:

Be it known that I, CHARLES A. WILLIAMS, a citizen of the United States, and a resident of Brooklyn, in the county of Kings and State of New York, have invented certain new and useful improvements in Multiple-Fuse Carriers, of which the following is a specification.

This invention relates to improvements in multiple fuse carriers or cartridges in which a plurality of fuses may be carried, so that when one fuse burns out another may be quickly and easily brought into position and the circuit at once restored, the object of the invention being to provide a device of this character which is extremely simple in construction and inexpensive to manufacture and easily operated, and to provide a combination of parts whereby the liability of destruction of the cartridge on the blowing out of a fuse is rendered very remote.

In the drawings accompanying and forming part of this specification, Figure 1 is a plan view showing the loaded cartridge secured in position for use; Fig. 2 is an end view of Fig. 1; Fig. 3 is a longitudinal section of Fig. 1; Fig. 4 is a cross-sectional view taken on the line 4—4, Fig. 1; Fig. 5 is a longitudinal section of the inner rotatable cartridge with the fuses secured thereto; Fig. 6 is a cross-sectional view taken on the line 6—6, Fig. 5; Fig. 7 is a cross-sectional view taken on the line 7—7, Fig. 5; Fig. 8 is a longitudinal sectional view of the casing or shell; and Fig. 9 is a cross-sectional view of said shell, taken on the line 9—9, Fig. 8.

Similar characters of reference indicate the same parts in all the figures of the drawings.

In the embodiment herein illustrated, the improved fuse carrier or cartridge consists of a cylindrical member 2 formed of some suitable non-conducting material, in which are secured a plurality of fuses 3 (four being shown herein). The fuses are secured to the member 2 at each end thereof in any suitable manner, as for instance by means of rivets 4, the heads of which project at the exterior of the member 2 and act as contact forming members for said fuses. The member 2 is inclosed within an exterior shell or casing 5 adapted to snugly fit the member 2, but to permit rotation thereof within said shell. The shell 5 is provided adjacent to each end thereof with a groove 15 extending

around its interior circumference and in position to receive the heads of the rivets 4 and permit them to rotate with the member 2. The shell 5 is also provided approximately midway of its length with two oppositely located openings 6 for permitting the member 2 to be taken hold of and turned by the fingers of the operator.

A pair of end members or caps 7, formed of a suitable metal, are provided for closing the ends of the cartridge, and which caps are adapted to fit over the ends of the shell or casing 5, the caps 7 having secured thereto suitable brackets 8 for attachment to any suitable support in position for use. Each of the end members or caps 7 has punched from the metal thereof a tongue 9, which is so formed and pressed inwardly as to project into a cutout portion or recess 10 in the end of the casing or shell 5 and form contact with whichever fuse is located in position so that its rivet is within said opening 10. The shell 5 is also provided with a small opening 1 near one end thereof, and the inner rotatable member 2 is marked on the exterior thereof directly over the point where each fuse is located with some suitable indicating character which will appear in said opening 1 when the member 2 has been rotated so as to bring one of the fuses into contact with the tongues carried by the caps. The tongues 9 and openings 10 also perform the function of forming a positive stop to prevent the rotation of the shell 5 relatively to the caps 7 when the inner tubular member 2 is rotated within said shell.

The fuses herein shown are formed of copper ends, as 12, united by a center portion 11 of a softer metal, such as a compound of lead and antimony, said center portion being offset from the cartridge, as shown clearly in Figs. 3 and 5, and in case of a blowout the weaker center portion of the fuse will break.

The cartridge 2, after having the required number of fuses riveted therein, is filled with asbestos powder, which will fill in the space between the wall of the cartridge and the center portion of the fuse, so that when a fuse is blown out ignition of any portion of the cartridge is prevented by reason of the fact that the asbestos powder will immediately fill in any space that is caused by the blowout, and the ends of the cartridge are closed by means of a pair of asbestos disks 13, which are perforated, as are also the end

walls of the caps 7, as shown in Fig. 2, for the purpose of permitting the escape of any gases that may be formed within the cartridge on the blowing out of a fuse.

- 5 From the foregoing it will be seen that after the cartridge has been "loaded" and placed within the shell or casing 5 and the latter properly placed within the caps 7, with the tongues 9 of said caps projecting 10 into the recesses 10 in the ends of the shell 5, the shell will be held against rotation relatively to said caps, and by taking hold of the inner member 2 through the openings 6 in the shell 5 the member 2 may be rotated 15 until one of its fuses is in contact with the tongues 9, which is indicated by the appearance of the indicating character in the opening 1 in the shell. It will thus be seen that when a fuse has blown out, all that is necessary is to take hold of the cartridge 2 through the opening 6 in the shell and rotate said cartridge a short distance thereby to bring the next fuse into position to contact with the contact members or tongues 9.
- 25 It will be understood, of course, that I do not desire to confine myself to the identical details herein shown and described, but that the same may be modified more or less without departing from the spirit and scope of 30 this invention.

I claim as my invention:

1. A multiple fuse carrier comprising a pair of similarly formed members one located within the other and one movable relatively to the other, one of said members carrying a plurality of fuses and the other adapted to permit manual operation of said fuse carrying member to bring the fuses successively into an electrical circuit, and 40 means carried by said fuse carrier for making electrical contact with one of said fuses.

2. A multiple fuse carrier comprising a pair of tubular members, one located within the other from end to end thereof and 45 rotatable relatively thereto, one of said members carrying a plurality of fuses and the other adapted to permit manual rotation of said fuse carrying member to bring the fuses successively into an electrical circuit, 50 and means carried by said fuse carrier for making electrical contact with one of said fuses.

3. A multiple fuse carrier comprising a pair of tubular members, one located within 55 the other from end to end thereof and rotatable relatively thereto, said inner rotatable member carrying a plurality of fuses and the outer member adapted to permit manual rotation of said fuse carrying member to bring 60 the fuses successively into an electrical circuit, and means carried by said fuse carrier for making electrical contact with one of said fuses.

4. A multiple fuse carrier comprising a 65 pair of similarly formed members one lo-

cated within the other and one movable relatively to the other, one of said members carrying a plurality of fuses and the other adapted to permit manual operation of said fuse carrying member to bring the fuses 70 successively into an electrical circuit, and means carried by said fuse carrier for making electrical contact with one of said fuses and for preventing movement of one of said members. 75

5. A multiple fuse carrier comprising a pair of similarly formed members one located within the other from end to end thereof and one movable relatively to the other, one of said members carrying a plurality of fuses and the other adapted to permit manual operation of said fuse carrying member to bring the fuses 80 successively into an electrical circuit, means carried by said fuse carrier for making electrical contact with one of said fuses, and coöperating means carried by said members for indicating the proper position of said fuse for making such contact. 85

6. A multiple fuse carrier comprising a 90 pair of tubular members, one located within the other from end to end thereof and rotatable relatively thereto, one of said members carrying a plurality of fuses and the other adapted to permit manual rotation of said 95 fuse carrying member to bring the fuses successively into an electrical circuit, means carried by said fuse carrier for making electrical contact with one of said fuses, and coöperating means carried by said members for indicating the proper position of said 100 fuse. 105

7. A multiple fuse carrier comprising a pair of tubular members, one located within and rotatable relatively to the other, said 110 inner rotatable member carrying a plurality of fuses and the outer member adapted to permit manual rotation of said fuse carrying member to bring the fuses successively into an electrical circuit, means carried by 115 said fuse carrier for making electrical contact with one of said fuses, and coöperating means carried by said members for indicating the proper position of said fuse and comprising characters carried on the inner 115 member and an opening in the outer member with which said characters are adapted to successively register. 120

8. A multiple fuse carrier comprising a pair of members one located within the other 125 and one movable relatively to the other, one of said members carrying a plurality of fuses and the other adapted to permit manual operation of said fuse carrying member to bring the fuses successively into an electrical circuit, means for closing the ends of said members, and coöperating means carried by said last means and the outer member for making contact with one of said fuses and comprising tongues carried by one 130

of said elements and projecting through openings carried by the other.

9. A multiple fuse carrier comprising a pair of members one located within the other and one movable relatively to the other, one of said members carrying a plurality of fuses and the other adapted to permit manual operation of said fuse carrying member to bring the fuses successively into an electrical circuit, a pair of caps for closing the ends of said members, and coöperating means comprising tongues carried by said caps and a pair of openings carried by the outer member for making electrical contact with one of said fuses.
10. A multiple fuse carrier comprising a pair of tubular members, one located within and rotatable relatively to the other, said inner rotatable member carrying a plurality

of fuses secured thereon, a portion of each of said fuses being offset from said member, the outer member being provided with openings to permit manual rotation of said fuse carrying member to bring the fuses successively into an electrical circuit, a fire-proof material within said inner rotatable member and adapted to fill in the space between said offset portions of the fuses and the rotatable member, a pair of end closing members for said inner member, and a pair of caps for closing the ends of said outer member and carrying means for forming electrical contact with one of said fuses.

Signed at Brooklyn, in the county of Kings and State of New York this 22nd day of December, A. D. 1916.

CHARLES A. WILLIAMS.
